UNITED STATES PATENT OFFICE

VINCENT E. POEPPELMEIER, OF DAYTON, OHIO

JUSTIFYING DEVICE

Application filed June 23, 1930. Serial No. 463,140.

This invention relates to type justification.

One object of the invention is the provision of a novel justifying type piece, quad or spacer, of variable width.

5 Another object of the invention resides in the method of arranging type by which words are formed from type in juxtaposed lines of different lengths, the distance between adjacent words being then varied to make the 55 lines all of the same length.

Other objects and advantages of the invention will be apparent from the following description, the appended claims, and the accompanying drawings, in which—

15 Fig. 1 is a view of a number of letter type arranged in a chase plate and having justifying spacers arranged between adjacent words in accordance with the present invention;

Fig. 2 is a section on the line 2—2 of Fig. 1;

20 Fig. 3 is an enlarged view of several letter type and justifying spacers, before justification has taken place;

Fig. 4 is a view corresponding to Fig. 3 after the spacers have been expanded to justify the distance between adjacent words;

25 Fig. 5 is a section on the line 5—5 of Fig. 3; Fig. 6 is a section on the line 6—6 of Fig. 4;

Fig. 7 is a side view of a justifying quad embodying the present invention;

30 Fig. 8 is a view of the quad in its expanded condition;

Fig. 9 is a front view of the quad shown in Fig. 7; and

35 Fig. 10 shows a modified form of quad adapted to be contracted during the justifying operation.

Referring more particularly to the drawings, in which preferred embodiments of the invention are illustrated, Fig. 1 shows a portion of a chase plate in which a number of type are arranged to form a series of words, formed in juxtaposed lines. The chase plate 10 in which the type is held is shown as of flat formation having type retaining grooves

40 11 in which the short cast letter type 12 is retained, but obviously the invention is not at all limited to a plate which is flat, or to type of any particular length.

45 In order to have all of the printed lines of the same length it is desirable to so arrange

the spaces between adjacent words that the ends of the lines will all be even. This has ordinarily been done in the past by calculations and intricate mechanical means and no practical or satisfactory method has ever been known for justifying type, especially hand set type, so that a series of lines are formed of exactly the same length. In accordance with the present invention, however, the type is so arranged that the lines are all 60 of the same length and the justifying operation is accomplished very rapidly and by an ordinary layman, and without the use of complicated or intricate apparatus.

55 In carrying this invention into effect, use is made of justifying type pieces, quads or spacers adapted to be used in or between adjacent words, the spacers or type pieces being of variable width. Preferably the spacers are formed integrally with portions at the

60 end thereof adapted to be forced apart or forced together so that a number of words may be suitably spaced after they have been arranged in the chase plate; and lines of the desired length are obtained. Such quads or spacers are shown at 13 in Fig. 1, this figure showing a number of justifying quads, all of

65 similar form and construction, arranged between adjacent words in the several lines of type. The words are formed of a number of individual type, each of which has a letter forming upper end, the type and the justifying quads being arranged in the type-retaining

70 grooves 11 either by hand or by a suitable type setting machine. Each individual piece of the letter type may be self-justifying, having an upper end portion of variable width, or as shown in the drawings, the justifying operation may be accomplished only

75 by varying the width of the spacer between adjacent words.

80 As shown in Figs. 7, 8, and 9 the quad or spacer 13, which as herein shown is adapted for use with short mold type, has a foot or base 15, neck 16, and a head 17. It is of a 85 height slightly less than the total height of the letter type with which it is used so that it will not cause any imprint upon the paper. Preferably it reaches up just slightly above the block portions of the letter type, as shown

in Fig. 5. The top end of the spacer or quad is formed so that its width may be varied. A preferred construction is shown in Fig. 7 in which the upper end of the quad is provided with two spaced wedge shaped projections 20 and 21, cast integrally with the quad, and normally having a total width less than the width of the body portion of the quad. The angle between the two wedge projections is 10 preferably about 60°.

The width of the quad shown in Fig. 7 is varied by forcing the two projections 20 and 21 apart so that they project out laterally beyond the sides of the quad and thus divide 15 adjacent words variably. The expansion can be accomplished by an ordinary center punch or by a wedge shaped chisel, or the like, which can be inserted between the wedge projections and struck by a hammer so that the two 20 wedge projections move apart and the quad is then as shown in Fig. 8, it being noted that the width of the quad is now greater than it was because the center punch has forced the intermediate portions of the wedge projections 25 outwardly beyond the sides of the body portion of the quad.

In Fig. 10 there is shown a modified form of quad which is cast so that the two wedge projections 23 and 24 normally extend outwardly beyond the sides of the body portion of the quad, and they may be forced towards one another by compression so that the total width of the quad is reduced.

When type is to be set, the proper words 35 are formed from the individual letter type, and a justifying quad is used between each pair of adjacent words, the various type being applied to the type-holding grooves 11 of the plate 10. The ends of the lines will be 40 uneven at first, for the number of letters in a line will vary, and there will be varying numbers of justifying quads in each line. The quads, of the form shown in Fig. 7, when 45 assembled between adjacent words will be of their minimum width. A marginal strip 25 is then applied to the plate, defining the maximum line length, and all of the other lines that may be shorter than the maximum line 50 length are then expanded by expansion of the justifying quads by striking them one after the other, preferably manually, it being understood that in those lines that must be expanded considerably the justifying quads are struck harder blows so as to expand them 55 a little more than those that may be in the longer lines. The quads in the longest line need not be struck at all, and only a few of the quads in the longer lines need be struck lightly; and of course a short line at the end 60 of a paragraph need not be lengthened at all. The justifying operation may be accomplished in a very short time, and no particular care is required to have the expanded justifying quads in any one line of exactly 65 the same width. The various lines of type

are thus very readily and in a few minutes time all made of uniform length and the set type is now ready for use.

Fig. 3 shows a number of letter type arranged with justifying spacers or quads, and Fig. 4 shows the same type after the spacers have been expanded and the line justified. In Fig. 5 the cross-sectional view corresponding to Fig. 3 shows the sides of the body portion of the quad in abutting relation with the sides of the adjacent letter type, while in Fig. 6 the quad has been expanded, and the distance between adjacent letter type is determined by the outwardly extending wedge projections 20 and 21.

The justifying quads may be used directly in an automatic typesetting machine, all of the quads being of the same form and construction and of a uniform width; or the type and the quads may be set by hand as 85 previously described. Preferably the width of a quad is about .07 of an inch, and in this size the type is adapted to be used directly in the automatic typesetting machine.

Instead of expanding the spacers to justify 90 juxtaposed lines of type, spacers such as are shown in Fig. 10 may be employed, and the various lines of type may be simultaneously forced or contracted to the same length as the shortest line, or to a desired length. In 95 this case the marginal strip 25 shown in Fig. 1, may be replaced by a heavier rigid bar which may be forced over by suitable mechanical means thus causing the simultaneous justification of all of the lines of type. 100 It will be understood that due to the tapering form of the projections 23 and 24 of the quads shown in Fig. 10, all of the spacers in a line will be compressed about the same amount, for the force required to bend the 105 wedge portions together varies approximately with the amount of compression taking place.

While the methods herein described, and the forms of apparatus for carrying these methods into effect, constitute preferred embodiments of the invention, it is to be understood that the invention is not limited to these precise methods and forms of apparatus, and that changes may be made in either without departing from the scope of the invention 110 which is defined in the appended claims.

What is claimed is:

1. A justifying type piece having a foot portion of definite width and having a top portion of variable width.
2. A justifying spacer for short mold type, having notched sides and a bottom foot of definite width, and having an irregularly formed top portion which is readily deformable to change the width of the spacer.
3. A justifying type piece having at one end thereof a pair of spaced wedge shaped projections adapted to be bent to change the width of the spacer.

4. An integral cast justifying short mold type piece having an expansible end and having a foot portion of definite width.
5. A justifying spacer having integrally formed wedge shaped projections normally occupying a total width not exceeding the width of the spacer and adapted to be forced apart so as to project out beyond the side body portions of the spacer.
- 10 6. A justifying spacer having a pair of wedge shaped projections normally projecting out along the body portions of the spacer and adapted to be forced towards one another to vary the total width of the spacer.
- 15 7. The method of arranging type comprising forming spaced words from letter type and spacers of the short mold type into juxtaposed lines of different lengths and then expanding the spacers to expand the distance between adjacent words in the shorter lines to make the lines of the same length.
- 20 In testimony whereof I hereto affix my signature.

VINCENT E. POEPPELMEIER.
